UNITED STATES PATENT OFFICE.

LUTHER T. HAZEN, OF COVENTRY, NEW YORK.

HUB FOR CARRIAGE-WHEELS.

Specification of Letters Patent No. 24,120, dated May 24, 1859.

To all whom it may concern:

Be it known that I, LUTHER T. HAZEN, of the town of Coventry, in the State of New York, have invented new and useful Improvements in Making Hubs for Carriage Wheels and other Vehicles; and the following is a clear description of the same, reference being had to the accompanying drawings, making part of this specification.

10 The nature of my invention consists in incasing wood hubs entirely with metal, which forms the pipe box and helps to hold firmly the spokes.

15 In order to enable others skilled in the arts to make and use my improved hubs I will describe it referring to the drawing.

Figure 1, represents a section through the center of the hub—the brown color, the iron case and pipe box, the orange color the 20 wood hub. Fig. 2 shows the plan with the front and case off.

(A) is a plain wood hub, turned in shape and size to fit the cavity in the castings, and is mortised to receive the spokes in the usual 25 manner.

(B) is the pipe box with the case (b) cast on the largest end which forms the shape and finish back of the spokes, and has a concave into which the wood hub is fitted.

30 (C) is a movable case, cast in form and shape like the one on the pipe box, and slides

onto it, and forms the finish of the hub in front of the spokes, together with the band (D) which makes the screw nut to hold the front case (c) to its place on the wood 35 hub (A).

It will readily be seen, that among the many advantages to be derived in my manner of making and incasing wood hubs, one of the greatest is, that they can be made 40 much lighter, and in better proportions than ordinary cast iron hubs, and much stronger, and more durable than wood hubs, which require to be made of the best quality of timber or they are liable to become split or 45 cracked and thereby the spokes become loosened. In my improved hub they require no other banding, and the case protects the hub from all exposure, and furthermore there is no liability of the pipe box becoming 50 loosened nor the wheel getting out of true.

Having thus fully described my invention, what I claim as new and desire to secure by Letters Patent, is, inclosing wood hubs for carriage wheels or other vehicles with metal 55 cases, which form the pipe box, and bands, in the manner described, and for the purposes set forth.

LUTHER T. HAZEN.
